DESIGN FOR A PERFUMERY BOTTLE OR SIMILAR ARTICLE

Herbert H. Harris, New York, N. Y.

Application March 6, 1940, Serial No. 90,723

Term of patent 7 years

To all whom it may concern:

Be it known that I, Herbert H. Harris, a citizen of the United States and resident of New York, in the county and State of New York, have invented a new, original, and ornamental Design for a Perfumery Bottle or Similar Article, of which the following is a specification, reference being had to the accompanying drawing, forming part thereof.

In the drawing:

Fig. 1 is a side view of a perfumery bottle showing my new design.

Fig. 2 is an edge view thereof.

Fig. 3 is a top plan view.

Fig. 4 is a bottom plan view.

I claim:

The ornamental design for a perfumery bottle or similar article, substantially as shown.

HERBERT H. HARRIS.
